UNITED STATES PATENT OFFICE.

CHARLES C. BECKER AND PHILIPP JACOB, OF CHICAGO, ILLINOIS.

LIQUID MEASURE AND SCALES.

SPECIFICATION forming part of Letters Patent No. 255,132, dated March 21, 1882.

Application filed October 28, 1881. (No model.)

To all whom it may concern:

Be it known that we, CHARLES C. BECKER and PHILIPP JACOB, both of Chicago, in the county of Cook and State of Illinois, have invented certain new and useful Improvements in Liquid Measures and Scales; and we do hereby declare that the following is a full, clear, and exact description thereof, reference being had to the accompanying drawings, and to the letters of reference marked thereon, which form a part of this specification.

This invention relates to measures for liquids, and more particularly for measuring that kind of liquid which, by filling into a vessel, will create a foam on its surface that prevents a true measure; and it is the object of our invention to provide a measure that will determine the exact amount by the weight of the liquid with which it is filled.

Therefore our invention consists of the parts and combination of parts, as hereinafter described and specifically claimed.

In the accompanying drawings, Figure 1 represents an exterior perspective view of the liquid-measure complete; Fig. 2, a sectional elevation of the same; Fig. 3, a cross-section on line *x* *x* in Fig. 2; Fig. 4, a section and elevation of the adjustable indicating-lugs and guide detached; and Fig. 5 is a detached view of one of the coiled springs.

Like letters represent corresponding parts in all the figures.

A denotes the measuring-vessel, which we prefer to make true cylindrical. This has attached to its rear a dovetail-like guide, *a*, in which right-angular lugs *b* will slide that are adjustably secured in any desired position, each by a set-screw, *c*, that is tapped through the shank of lug *b*, sliding in the dovetail guide.

D is a cylindrical frame that is open at both ends, with an internal diameter for the vessel *A* to be inserted and to slide vertically therein. This frame *D* has a handle, *d*, of any usual shape, and at the side where the handle is attached said frame is slotted for the dovetailed guide *a* to slide freely up and down therein. The handle *d*, at its upper junction with frame *D*, is also slotted for the lugs *b* to pass through it. Against each side of the frame *D*, and di-

ametrically opposite each other, are secured 50 against the frame two semi-cylindrical tubes, *f*, that are closed on top and open at the bottom. Two tubes, *g*, that are open at the top and closed at the bottom, are of a diameter to enter and slide vertically in the tubes *f*. These 55 tubes *g* are connected at the bottom by a wire, *h*, so that the tubes *g* and wire *h* combined form a U-shaped yoke. Coiled springs *i*, of a size to enter tubes *g*, are secured each with one end to the cap of one of the tubes *f*, and with 60 their opposite ends to the bottom of tubes *g*, so as to pull said tubes *g* and wire *h* upward with the wire bearing against the lower edges of frame *D*. The bottom of the vessel *A* will rest upon the wire *h*, and will be balanced by 65 the springs *i*, which, by filling liquid in said vessel, will be expanded proportionally, and by the distance the vessel *A* will sink down in the frame the amount of liquid the vessel contains will be indicated. According to the 70 specific gravity of the liquid which is to be measured the lugs *b* are adjusted for measuring a pint or quart. The projecting shank of lugs *b* is shaped for pressing the thumb thereon while supporting the measure by the handle, so as to hold the intended lug even with the top of said handle, when by filling the vessel *A* the bar-tender can feel how the pressure of the lug against his thumb becomes less 75 until the pressure is counterbalanced by the weight of the liquid, when he knows he has the correct measure, no matter if in the shape of foam or liquid.

This apparatus is particularly intended for measuring fermented liquors—as beer, ale, or 80 porter; but it may be used for measuring other liquids.

As will be noticed, this measure is very simple in its construction, cannot well get out of order, is easily handled, and is always ready 85 for use.

This device is also well adapted for measuring off combustible liquids—like gasoline, benzine, or alcohol—at night without light.

What we claim is—

1. The combination of the vessel *A*, having dovetailed slide *a* and vertically-adjustable lugs *b* and set-screws *c*, and the frame *D*, hav-

ing wire *h*, suspended therefrom by coiled springs *i*, all substantially as and for the purpose set forth.

2. The combination, with vessel *A*, having 5 dovetail slide *a*, vertically-adjustable lugs *b*, and set-screws *c*, of the frame *D*, having slotted handle *d*, tubes *f*, spring-inclosing tubes *g*, transverse connecting-wire *h*, and springs *i*, all substantially as and for the purpose set 10 forth.

In testimony that we claim the foregoing as our invention we affix our signatures in presence of two witnesses.

CHARLES C. BECKER.
PHILIPP JACOB.
